UNITED STATES PATENT OFFICE.

ROBERT W. BANKS, JR., OF GULFPORT, MISSISSIPPI.

BLADE-SHARPENER.

1,145,053.

Specification of Letters Patent.

Patented July 6, 1915.

Application filed April 26, 1913. Serial No. 763,884.

To all whom it may concern:

Be it known that I, ROBERT W. BANKS, Jr., a citizen of the United States, residing at Gulfport, in the county of Harrison and 5 State of Mississippi, have invented certain new and useful Improvements in Blade-Sharpener, of which the following is a specification.

My invention relates to blade sharpeners, 10 particularly adapted for the sharpening of razor blades.

One object of the invention is to provide means whereby the parts may be adjusted so that the blade can be reversed to facilitate either honing or stropping.

A second object is to provide means whereby the blade upon reversal, may be moved into engagement with the sharpener member without shock such as would tend 20 to cause injury to the blade as by nicking thereof.

A third object is to provide means for the reversal of the blade utilizing a gear member and a reversing member movable to 25 bring opposite faces or walls into engagement with the gear member.

A fourth object is to provide means whereby the blade may be carried by and actuated through the movement of a plurality of slidable carriages or frames movable as a unit at times and movable independently of each other at times.

A fifth object is to provide a construction wherein a relatively narrow sharpener member 35 preferably arranged diagonally with respect to the edge of the blade, may be employed.

Other objects of the invention are to generally improve and simplify the construction of a device of this kind, due regard having been given to cost of manufacture and the durability of the parts when used.

The preferred form of the present invention, is described hereinafter and illustrated 45 in accompanying drawings.

In said drawings:—Figure 1 is a side elevation of the machine; Fig. 2 is a plan view; Fig. 3 is an end view; Fig. 4 is a perspective view of one of the slidable frames or members employed; Fig. 5 is a perspective view of the other slidable member or frame employed; Fig. 6 is a side elevation of one of the guard plates employed; and Fig. 7 illustrates in side elevation and perspective, one

form of sharpener member which may be used.

Like reference characters designate like or similar parts throughout the several views of the drawings.

Referring specifically to the drawings, a main frame is provided consisting essentially of the side walls or members 1 joined by the end walls or members 2. Mounted in the end walls 2 intermediate the side walls 1, are suitable rods or rails 3 shown in the form of bolts having at opposite ends screw threaded shanks which pass through the end walls and beyond the same receive nuts 4. These rods 3 pass through openings 5 provided in lugs 6 of a slidable carriage generally designated 7 and thus serve to slidably mount said carriage longitudinally of said rods. The lugs 6 below the rails 3 are surrounded by coil springs 8 which bear against the rails and portions of the slidable carriage and serve to create some degree of friction between the rods and walls at openings 5, in order to maintain the parts supported by the carriage in proper position and prevent too loose movement of the carriage. This carriage member 7 is provided with side plates 9 having provided at their upper ends, openings or apertures 10.

Numeral 11 generally designates a second slidable member which is provided with side walls 12 and 13, each having therein an elongated slot or opening 14. This slidable member 11 is supported from the carriage or slidable member 7 by means of suitable lugs shown in the form of set screws 15, and which are adapted to pass through the slots 14 and enter screw threaded openings in the walls 9, thus serving to fasten the second slidable member to the carriage. It is to be noted that a pair of lugs 15 is provided for each opening 14 and that the distance from the centers thereof is less than the length of the slot so that the second slidable member is capable of a limited sliding movement relative to the carriage and independently thereof.

In the openings 10, is rotatably mounted a shaft 16 of a blade carrier device. This shaft also extends through an elongated opening 17 in the wall 13. On the outer face 105 of wall 13 is slidably and adjustably mounted a reversing plate member 18 by means of lugs in the form of set screws 19, located at

opposite ends of the plate and passing through elongated slots 20 thereof and fastening to the wall 13. A substantially rectangular opening opposite the slot 17, is provided in the plate 18, and the opposed longitudinal walls thereof at different times are adapted to be brought into driving relation with a gear member 21 mounted on the shaft 16. This gear member as shown, is in the form of a gear wheel having teeth, and accordingly the longitudinal edges or walls of the rectangular slot of plate 18, are serrated or toothed at 22 and 23 to provide racks. It will be noted that the oblong opening is of such width that when the teeth of gear wheel 21 mesh with the teeth of either of the racks, the teeth of the other rack are disengaged. Suitable means is provided so that the reversing plate may be shifted to cause the proper or desired rack 22 and 23 to mesh with the gear 21. This means as shown, consists of an eccentric 24 extending through an elongated slot 25 of the plate and having thereon a finger or grip piece 26. In addition to the shaft 16, the blade carrier device may comprise a suitable blade holder 27 and an arm 28 rigid with shaft 16 and having an offset portion or lug 29 thereon.

As is obvious, the blade holder may be of any suitable construction, but as shown, comprises clasp leaves 30 between which the blade such as 31, is gripped. These clasp leaves are supported from shaft 16 so as to rotate therewith, and are yieldingly held together by means of suitable spring clips 32 which engage the shaft 16. Each of the clasp leaves is provided with a lug 33 and these lugs extend on opposite sides of the arm 28. Also each clasp leaf is provided with a finger piece 34, whereby when both of said finger pieces are moved toward each other, the clasp leaves may be spread apart for the removal or reception of a blade such as 31.

Extending obliquely across the machine or frame, and suitably fastened as to the side plates 1, is a rest plate 35 having on each longitudinal edge thereof, upstanding lugs or clips 36. Upon this plate 35 is adapted to rest, a sharpener member generally designated 37. This sharpener member it will be noted, is of very narrow width and it is especially desirable to employ such a narrow one, inasmuch as I have found that better results can be obtained when it is used, than when a wider one is employed. In actual use, I have found that this sharpener member should not be more than three eighths of an inch in width. Preferably this sharpener member should have a hone section 38 such as stone or other abrasive material and a strop section 39 such as leather. This sharpener member is shown as a unit, and the hone and strop are connected together in any suitable manner.

To either of the side plates 1 may be fastened at opposite ends, guard plates generally designated 40 which are adjustably secured to the plates by means of bolts 41 extending therethrough and through elongated slots 42 of the guard plates. One end of each plate is mounted on a line taken transversely of the frame adjacent the ends of the sharpener member. Each guard plate is provided with a deflected or inclined wall 75 43 which leads downwardly toward the sharpener member. These guards 40 are so arranged as to be engaged by the arm 28, or more specifically its lug 29 upon reversal of the blade 31 while at the extremity of its 80 movement or practically so.

To facilitate manipulation of the parts, a handle 44 is suitably fastened to one end plate 2, and a handle 45 extending at right angles to the handle 44 is suitably fastened 85 to the second slidable carriage 11.

Preparatory to use, according to whether or not the razor or other blade 31 is to be honed or stropped, the proper rack 22 or 23 is brought into driving relation with the 90 wheel 21 through the inter-meshing of the teeth of said parts. As is well known in the art, the blade is moved in the opposite direction for stropping to that in which it is moved for honing. Through the adjustment 95 of the reversing plate 18 to bring the proper rack into driving relation with the wheel 21, the proper direction of movement can be provided for. As stated, this plate 18 is shifted through the manual adjustment of 100 eccentric 24, and in its movement the plate is guided by the lugs 19 at openings 20.

The adjustment aforesaid having been attained, and the blade 31 clasped by the leaves 30, the handles or grips 44 and 45 are engaged by separate hands and moved relatively, which causes the blade 31 to move upon the sharpening member and upon either the hone or strop, according to which side thereof is uppermost. When the carriage 7 and slidable member 11 are moved, the engagement of the blade 31 with the sharpening member of course, prevents rotation of the gear 21. However, when the approximate extreme of the movement of this 110 carriage and slidable member at either end of the machine, has been reached, the handles 44 and 45 are moved in the proper direction so as to cause the slidable member 11 to move in the opposite direction, which causes the proper rack to shift the gear wheel 21 and accordingly partially rotate and reverse the blade 31. During this reversing movement, the slidable member 11 moves independently of the slidable carriage 120 7, the latter remaining stationary until the blade 31 on its opposite edge engages the sharpener member. This carriage is enabled to remain stationary in this manner, due to the frictional engagement of the 125 130

walls of openings 5 with the rails 3, increased by the provision of the springs 8 as described. The action of the several parts upon the movement of the handles relatively, is automatic as will be realized. Upon the blade 31, descending, the lug 29 engages the upper edge of the guard member 40, or the edge of the blade engages the sharpening member. In this way, shocks of the blade against the sharpening member and consequent nicking of the blade, is avoided. After lug 29 has thus engaged the proper guard 40, the slideable members are moved in the reverse direction and said lug 29 moves on the deflected face 43, and gradually and without shock onto the sharpening member. This action is true of course, upon reversal of the blade at either end of the machine. It might also be stated that prior to operation the guards 40 should be in proper relation to the sharpening member, according to the width or size of the blade to be sharpened. In order to accommodate the device for the sharpening of blades of different sizes or widths, the guard members 42 may be adjusted longitudinally of the frame and relatively to the sharpening member through the adjustment of the bolts 41.

Various changes may be made in the details of construction of the device described and illustrated herein, but insofar as such changes fall within the spirit and scope of the appended claims, they are accordingly reserved.

Having thus described my said invention, what I claim as new and desire to secure by Letters Patent is:—

1. In an apparatus of the class described, a sharpening member, a frame therefor having rails, a blade-carrying device movable relatively to said member having a plurality of slideable members, one of said members mounted on said rails, means to maintain said one slideable member in frictional engagement with said rails, said one slideable member having walls each having a projection thereon, the other slideable member provided with walls having elongated slots in which said projections enter, said projection and slot connections permitting movement of one of said slideable members relatively to the other, a plate adjustably mounted on one of said latter walls, a shaft supported by one of said slideable members, a blade holder carried by said shaft, a gear wheel on said shaft, said plate provided with opposite racks, guide means for said plate, and an eccentric operable to shift said plate to selectively bring a selected one of said racks into engagement with said gear wheel.

2. In an apparatus of the class described a frame including supporting rods, a sharpening member carried by said frame and extending above said rods, a carriage carried

by said frame and comprising a plurality of slideable members, one of said members being provided with perforated ears slidably mounted upon said rods and with end walls positioned outside said frame, means carried by said ears for causing frictional binding between said ears and rods, the other of said slideable members comprising a plate extending beneath said first-mentioned member and having end walls extending outside the walls of said first-mentioned member and provided with transversely extending slots, means passing through said slots to slidably connect said members, a rack adjustably connected with said second-mentioned slideable member and provided with upper and lower rows of teeth, a rocker shaft carried by said first-mentioned slideable member, a gear wheel carried by said shaft for engagement with the teeth of said rack, means for adjusting the position of said rack to bring a selected set of teeth in engagement with said gear wheel, and a blade-holding element carried by said rocker shaft.

3. In an apparatus of the character described, a track, a sharpening member carried by said track, and a carriage carried by said track, and comprising an inner member slidably connected with said track, a slideably mounted outer member engaging said inner member and having independent sliding movement longitudinally of said track with respect to said inner member, a rocker shaft carried by one of said members, a pinion carried by said rocker shaft, a rack adjustably carried by the second member and provided with teeth positioned upon opposite sides of said pinion, means for moving said rack to an adjusted position to bring a selected set of teeth into engagement with said pinion, and blade holding means carried by said rocker-shaft.

4. In a device of the character described a track, a sharpening member carried thereby, and a carriage carried by said track and comprising an inner member slidably connected with said track, an outer member slideably connected with said inner member, a rocker-shaft carried by said inner member, a pinion carried by said shaft, a rack adjustably carried by said outer member and provided with teeth positioned upon opposite sides of said pinion whereby a selected set of teeth may be brought into engagement with said pinion, and a blade holder carried by said shaft.

5. In a device of the character described a track, and a carriage slidably mounted upon said track and comprising an inner member, an outer member slidably mounted with respect to said inner member, a rocker-shaft carried by one of said members, a pinion carried by said shaft, a rack adjustably carried by the other of said members and provided with sets of teeth

positioned upon opposite sides of said pinion, means for moving said rack to bring a selected set of teeth into engagement with said pinion, and a blade holder carried by said shaft.

6. In a device of the character described a track, a sharpener holder carried by said track, and a carriage slidably connected with said track and comprising a supporting member, a slidably mounted actuating member engaging said supporting member, a rocker-shaft carried by said supporting member, blade holding means carried by said rocker-shaft, a pinion carried

by said rocker-shaft, a rack carried by said actuating member and provided with sets of teeth positioned upon opposite sides of said pinion, and means for moving said rack to an adjusted position to bring a selected set of teeth into engagement with said pinion.

In testimony whereof I affix my signature in presence of two witnesses.

ROBERT W. BANKS, Jr.
